Des. 240,272
Patented June 8, 1976

240,272

PUMP MANIFOLD

George M. Philpott, 43-485 Tennessee,
Palm Desert, Calif. 92260

Filed May 28, 1974, Ser. No. 473,704

Term of patent 14 years

Int. Cl. D15—02

U.S. Cl. D65—1 R

FIG. 2

FIG. 1

FIG. 3

FIG. 4

FIG. 5

FIG. 6

FIG. 7

FIG. 1 is a front elevational view of a pump manifold showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and

FIG. 7 is a cross sectional view taken on line 7—7 of FIG. 2, but with the discharge outlet in a rotated position.

The clamps have been omitted from FIGS. 2, 3, 5, 6 and 7 for convenience of illustration.

I claim:

The ornamental design for a pump manifold, as shown and described.
